No. 658,439.

Patented Sept. 25, 1900.

I. L. HARRIS.

ACETYLENE GAS GENERATOR.

(Application filed Jan. 29, 1900.)

(No Model.)

UNITED STATES PATENT OFFICE.

ISAAC LEONARD HARRIS, OF JACKSONVILLE, FLORIDA.

ACETYLENE-GAS GENERATOR.

SPECIFICATION forming part of Letters Patent No. 658,439, dated September 25, 1900.

Application filed January 29, 1900. Serial No. 3,086. (No model.)

To all whom it may concern:

Be it known that I, ISAAC LEONARD HARRIS, a citizen of the United States, residing at Jacksonville, in the county of Duval and State of Florida, have invented certain new and useful Improvements in Acetylene-Gas Generators, of which the following is a specification.

My invention relates to a machine for generating illuminating-gas from the reaction of calcium carbid and water; and the object of my invention is to bring the two compounds referred to into contact in such a manner as will produce the most effective results, and particularly in the volume of gas generated.

My present invention relates to a carbid-chamber, a generator-tank, a condenser, and a gasometer, all embodied in one piece, and includes a carbid-feeding device operated by a weight, which are modifications of the feeding device and operating mechanism treated of in my Letters Patent No. 637,252, dated November 21, 1899.

In the accompanying drawings, Figure 1 is a vertical section through the generator, condenser, and gasometer; Fig. 2, a similar section at right angles to Fig. 1 with the carbid-chamber in elevation; Fig. 3, an elevation of the outside casing, with a section through the sprocket-and-chain receptacle; Fig. 4, a plan. Figs. 5 and 6 are enlarged details of a part plan and elevation of the chain-belt-moving floor modification of my aforesaid Letters Patent, and Fig. 7 is a section of the water-escapement check-drum.

Similar figures refer to similar parts in the several views.

Features that I have already patented and which I claim in combination with this application are referred to by letters.

1 is a gasometer-casing, and 2 is a gasometer-bell, through the center of which is an opening extending its full depth, provided with a conical casing 3.

4 is the carbid-chamber partly contained in the conical casing 3 of the gasometer-bell, with which it forms a water seal, but above which it projects upward to a height equal to the upward limit to which the bell will rise when filled with gas. The carbid-chamber stands in an upright position in the middle of the gasometer, its lower portion being

cone-shaped and concentric to the conical casing 3 of the gasometer-bell when the latter is down at its lower point. The upper portion of the carbid-chamber is cylindrical from the point where the cone portion terminates to the top, where the charging-hole is located, closed by a cap-screw 5. The floor of the carbid-chamber consists of two parts, one part thereof being a solid floor 6, upon which the carbid falls when charged into the chamber from the opening at the top, the other part being composed of an endless chain belt 7, which is a modification of my Letters Patent previously referred to. The solid floor 6 partly rests on a fixed plate 8 and partly on a fixed round bar 9, with which it forms a hinge-joint. The object of this hinge-joint is to enable the floor to rise slightly for the purpose of relieving any obstruction in the shape of a piece of carbid which may have become lodged between it and the chain belt 7. This chain belt 7 is a close belt composed of flat plates 7^a, Fig. 5, turned under to form a link 7^b at the abutting-joints the full width of the belt. Throughout the entire circuit of the belt on both margins are inserted wire staples 7^c, one staple to each link and each staple being confined to the same link. To hold the staples together and thereby compose the links to form the belt, short cylindrical rings 7^d are used, which also serve the purpose of shoulders against which pressure can be brought to bear for moving the belt.

10 are two disk pulleys fastened to the revolving shaft 11, which works in bearings in the two side casings 12. These two disk pulleys carry the chain belt 7 near its two margins, as shown in dotted lines on Fig. 2.

13 are two sprocket-wheels, only one of which are shown, fastened to the revolving shaft 14. These two sprocket-wheels also carry the chain belt 7, the marginal wire staples 7^c engaging in the teeth of the sprockets. When the revolving shaft 14 turns, the teeth of each sprocket-wheel press against the cylindrical rings 7^d, (see Fig. 6,) forming part of the chain belt 7, and cause the entire belt to move. The disk pulleys 10 revolve in unison with the chain belt. Owing to the carbid only resting on the belt 7, where it is firmly supported by the disk pulleys, there is no slack in the belt on the upper side except at

the commencement of the movement to operate a discharge. At that moment the sprocket-wheels carry the slack of the chain to the upper side; but when the under side becomes 5 taut the descending carbid hurries the chain forward until the slack again forms on the under side at the termination of each discharge.

15, Fig. 3, is a sprocket-wheel also fastened 10 to the revolving shaft 14 at its outer end.

16 is an endless sprocket-chain which engages in the sprocket-wheel 15, and after passing downward and under two loose pulleys 17 and 18 passes upward and engages in and 15 over another sprocket-wheel 19, fastened to a revolving shaft 20. The shaft 20 is the motor-shaft, which carries the power for operating the carbid-feeding part of the machine. Fastened onto the shaft 20 is a water-escapement 20 check-drum C, which carries on its outer circumference a ratchet-wheel R. Against the drum C and also fastened onto the shaft 20 is another and smaller ratchet-wheel S, which is engaged by a pawl P, fastened to a rope- 25 drum D. Around the rope-drum D is wound a rope E, which carries a weight W. The rope-drum D revolves loosely on the shaft 20. All these parts on the shaft 20 indicated by letters are part of my Letters Patent No. 637,252, 30 previously referred to.

21 is a pawl which engages in the ratchet-wheel R, having a fulcrum 22, Fig. 3.

23 is a rod riveted loosely to the pawl 21 at the joint 24. This rod passes upward through 35 the guide-lug 25, above which it is bent inward at 26 until it extends under the projecting top of the gasometer-bell 2.

27 is a series of hanging strips depending 40 from a fixed round bar 28, on which they work loosely side by side in sufficient numbers to extend across the full width of the opening at the bottom of the carbid-chamber 4. The object of these strips is to destroy the tendency of the carbid to fly in all directions when 45 being charged into the chamber and to control it when being delivered from the chamber into the generator-tank.

29 is the generator-tank to hold water, having 50 a fixed grating 30, onto which the carbid falls, a hand-hole 31, closed by a cap-screw, and a mud-valve 32. Attached to the generator-tank is a receptacle 33 to hold the stagnant liquid medium through which the sprocket-chain 16 passes in conveying motion 55 from the sprocket-wheel 19 to the sprocket-wheel 15, the object of which is to prevent the escape of gas through the journal of the generator-easing where the shaft 14 enters, and thus obviate the necessity of a stuffing-box.

60 34 is a gas-pipe with a valve 35 for conveying the newly-generated gas from the generator-tank into a condenser 36, intermediate between the generator-tank and the gasometer, embodied within the gasometer, and 65 through which the gas must pass before it enters the gasometer. The newly-generated gas in an acetylene-gas generator is not pure

acetylene gas, but a mixture of acetylene gas and water-vapor. The condenser 36 removes the water-vapor from the gas by causing the 70 mixture to reverberate from side to side, as shown by the arrows passing around the subdivisions 37, which compel it to give up its water-vapor against the cold sides of the condenser, whereupon the fixed gas or acetylene 75 enters the gasometer as acetylene gas.

38 is a service-pipe for delivering the gas from the gasometer for consumption.

The operation of the machine is as follows: A quantity of water is put into the generator-tank 29 through the hand-hole 31 until it reaches the level shown on drawings, entirely submerging the grate 30. A quantity of calcium carbid is also charged into the carbid-chamber 4 through the opening 5. The tendency of the carbid to fly in all directions is checked by the hanging strips 27. The pawl 21 is now lifted by hand. This releases the ratchet-wheel R and allows the weight W to descend. The descent of the weight W causes 90 the rope-drum D to revolve by virtue of the rope E, with which it is wound, and the pawl P, engaging the smaller ratchet-wheel S, communicates its motion through the ratchet-wheel to the shaft 20, on which the sprocket-wheel 19 is fastened, causing it to revolve. The endless sprocket-chain 16 carries the motion of the shaft 20 to the shaft 14 through the sprocket-wheels 19 and 15, causing the two sprocket-wheels 13, engaging in the chain belt 7, to revolve and thus move the chain belt 7, on which carbid rests, until a portion of the carbid falls over the descending face of the belt into the generator-tank, and the generation of a relative quantity of gas is the result. 105 After entering the water in the tank the carbid is supported near the surface by the grating 30, where a chemical reaction takes place, the products of which are acetylene gas, which rises out of the water, and hydrate of lime, 110 which falls through the grating and settles at the bottom of the tank. The newly-generated gas enters the gasometer by the pipe 34 through the condenser 36, and the bell 2 of the gasometer rises upward. When the gasometer lowers, owing to the consumption of its contents, the projecting top or cover of the bell 2 comes into contact with the rod 23, bent under it for the purpose, pressing it 115 downward. This raises the pawl 21, again releasing the ratchet-wheel R, and the generation of a relative quantity of gas is repeated. When the bell of the gasometer rises and the rod 23 is relieved of its pressure, the pawl 21 reengages the ratchet-wheel R, 120 and the feeding of carbid into the generator-tank is stopped for the time being. To prevent a too rapid descent of the weight W and the consequent overcharge of carbid into the water-tank, the water-escapement 125 30 check-drum C is fastened unto the shaft 20, with which it revolves. This drum is divided into compartments inside partly filled with water, and when it revolves the water

passes from one compartment to the other with a velocity limited by the size of the openings C', Fig. 7, between the compartments. This controls the speed of the drum, 5 and consequently the speed of the entire mechanism of the carbid-feed. The weight W can be wound up at any time without interfering with the working of the generator.

Having thus described the nature of my invention, what I claim as new, and desire to secure by Letters Patent, is—

1. In an apparatus for the generation of acetylene gas in combination with a water-tank, the carbid-chamber, the moving chain belt 7 at the delivery end of the floor of the carbid-chamber, for feeding the carbid into the generator-tank and from under the solid part of the floor of which it emerges, said chain belt comprising an endless series of transverse plate-links fastened closely together, the open marginal links of the chain belt 7 composed of the staples 7^b and the cylindrical rings 7^c, the two sprocket-wheels 13 and the revolving shaft 14 onto which they are 25 fastened so distanced apart as to enable them to engage in the open marginal links of the chain belt which they operate and the disk pulleys 10 fastened to the idle shaft 11 over

which the chain belt works loosely substantially as shown.

2. In an acetylene-gas generator in combination with a water-tank and a carbid-chamber, the mechanical feeding device inside the generator for discharging carbid into the water-tank, the motor on the outside of the generator for operating the mechanical feeding device, controlled by the movements of the bell of the gasometer, the device for transmitting the power of the motor from the outside to the inside of the generator consisting 35 of a pair of sprocket-wheels located one within, one without a gas-generating chamber, separated from each other by a liquid seal consisting of a U-shaped receptacle containing liquid, and in each arm of which is contained one of said wheels, the said wheels being operatively connected by a sprocket-chain passed beneath the surface of the liquid, and beneath idle pulleys, whereby the motion is communicated from one wheel to 40 the other without permitting the escape of gas. 45

ISAAC LEONARD HARRIS.
